FLORAL ROPING MACHINE

William Rapaport, 8107 Sorrento, Detroit 28, Mich.

Filed Jan. 29, 1959, Ser. No. 789,861

1 Claim. (Cl. 41—3)

This invention relates to a machine for binding together foliage to form an elongated string of floral roping such as is used in festoons.

The present invention falls within a well-known class of machines in which a first string or wire is spirally wound along a second string or wire so as to entrap foliage between the two. The resulting product appears to be a continuous bough. On closer inspection it is found to include one wire or string which runs axially along the length of the roping; a plurality of boughs placed end to end with their central branches adjacent to the longitudinal wire; and another wire which spirals about the boughs and the longitudinal wire joining them together.

Machines of this type include a support for the wire or string which is to form the longitudinal member and means for drawing it through a central aperture in a rotatable ring which carries one or more spools of wire. The ring is adapted to rotate about the axis of the longitudinal string. The ring must be powered by a source such as an electric motor for a slow rotation. The longitudinal string must be moved through the central aperture of the ring in a generally timed relation to that rotation. The motion of the longitudinal string may be powered or obtained manually.

An operator first affixes the end of the wire which is supported on the ring to the longitudinal string. Then, as the string is fed through and the ring is rotated he inserts foliage such as evergreen boughs between the string and the wire so that they are captured as the rotation of the ring causes the wire to spiral about the constantly feeding string.

In a common type of machine which was used previously to the present invention the rotatable ring which supported the spirally wound wires was powered by a belt or chain which partially encircled the ring and was energized by a pulley or cogwheel driven by the motor. In using such a machine difficulty was experienced because of the entanglement of extending arms of the boughs with the ring driving means. The boughs or foliage which are utilized in the machine are necessarily of a non-uniform nature. They may therefore easily become entangled with the belt as it moves with respect to the ring. The present invention contemplates a method of suspending the ring and powering it and supporting it with respect to the machine which eliminates the danger of the foliage entangling in the driving mechanism. Moreover, it provides a convenient and efficient supporting platform for the foliage as it is fed into the string and wire.

Generally speaking the present machine comprises two rectangular boards which are supported at right angles to one another. The horizontal board forms the table of the machine and provides a convenient support for the boughs as they are fed into the machine. It contains an elongated slot through its center parallel to one of its sides. The vertical board is supported in this slot which provides clearance for the rotation of a ring sup-

2

ported in a central aperture in the vertical board. The ring is rotatably supported within the board by a series of support bearings which are affixed to the board externally of the aperture and make contact with spaced points on the perimeter of the ring. A driving wheel makes contact with a point on the perimeter of the ring and frictionally engages it causing the ring to rotate. This driving mechanism is supported below the horizontal board.

10 Other applications, advantages and objects of the present invention will be made apparent by the following detailed description of an embodiment of the invention. The description makes reference to the accompanying drawing which is a perspective view of the machine of the preferred embodiment with portions cut away to increase the visibility of critical areas.

The machine is supported by four corner legs 10 which terminate at their upper ends in a horizontally-supported table 12. The table is rectangular in configuration and is divided into two sections by a slot 14 which runs through the entire length of the table at its center and is bounded on its edges by two rails 16, which, together with two rails 18 which run along the opposite edges of the table, act as a supporting frame.

20 A second, lower table 20 is disposed parallel to the upper table 12 at a point midway between the table 12 and the lower terminations of the legs 10.

A vertical support member 22 which is generally rectangular in shape and may be formed of a thin sheet of wood as may be the tables 18 and 20 is disposed in the slot 14 at right angles to the tables 12 and 20. The vertical support member 22 has two legs 24 which extend from its lower edge at opposite sides and rest on the upper surface of the table 20.

30 A circular ring 26 is rotatably supported on the vertical member 22 by four support bearings 28 which are arranged at regular intervals about the outer perimeter of the ring 26. The support bearings 28 are journaled on pegs 30 which are affixed on the face of the vertical member 22. The outer perimeter of the support bearings are grooved to engage the perimeter of the ring 26.

The vertical member 22 has an aperture slightly larger than the hole 32 in the ring 26. These holes are aligned so that a clear sight is provided through the hole 32.

40 The ring 26 rotatably supports a wire reel 34 by means of a stud 36 which is fixed in the face of the ring 26. Tensioning means (not shown) taking the form of wire springs, are placed between the face of the ring 26 and the adjacent face of the spool from turning unless tension is placed on its wire.

50 A plurality of holes 36 spaced at regular intervals in the face of the ring 26 lower its total weight so to decrease its moment of inertia and make it easier to start and stop.

55 The ring 26 is energized by an electric motor 38 which is supported on the lower table 20. The electric motor has a rubber grooved pulley 40 fixed on its shaft. The pulley 40 makes contact with the outer perimeter of the ring 26 and frictionally drives it.

60 An eyelet 42 is supported on the ring 26 at approximately 120 degrees from the spool 34. The wire from the spool 34 passes through the eyelet 42 before connecting to the longitudinally moved wire.

In operation the end of the wire on spool 34 is first 65 placed through the eyelet 42 and then attached to one end of a wire or string 44. The string 44 is inserted through the hole 32 and the ring 26 and pulled through the hole 32 at a constant speed. It may be manually pulled through the hole or connected to a powered reel which will achieve the motion. At the same time the motor 38 is energized causing the spool 34 to rotate in an orbit about the string 44. Boughs of cedar or ever-

green are then held so that their forward edge is caught between the wire and the string 44. They are then drawn through the hole 32 and the wire is spirally wound around the bough and the string 44. When the end of a bough has been wrapped another bough is inserted into position so as to form a roping of the foliage. The speed at which the wire 44 is drawn through the hole 32 must be adjusted with respect to the speed of rotation of the ring 26 to achieve an optimum binding effect with a minimum use of wire.

Having thus described my invention, I claim:

A machine for spirally winding a first string about a second string so as to entrap foliage between the two in such a manner as to form floral roping, comprising: a horizontally disposed table having a slot extending substantially across its width; a vertical support member disposed in the said slot with a portion of its surface extending above said slot and a portion of its surface extending below said slot; a central circular aperture in said vertical support member; a plurality of bearings 15

5

10

15

rotatably supported on the surface of said support member at regular intervals with respect to one another about the perimeter of said central aperture and having their axes of rotation extending normally to the surface of said vertical support member; an annular ring having its outer perimeter journaled in said bearings so as to allow for rotation about a horizontal axis; a wire spool rotatably supported on said ring; an electric motor disposed below said table with its shaft in a horizontal position; and a circular rubber drive member disposed on the shaft of said motor with its perimeter in pressured engagement with the perimeter of said ring in such a manner as to impart rotation thereto.
